UNITED STATES PATENT OFFICE.

HENRY MATHER, OF NEW YORK, N. Y., ASSIGNOR OF ONE-HALF OF HIS
RIGHT TO JAMES BRYAN, OF SAME PLACE.

GATE-VALVE.

SPECIFICATION forming part of Letters Patent No. 225,711, dated March 23, 1880.

Application filed July 24, 1879.

To all whom it may concern:

Be it known that I, HENRY MATHER, of New York, in the county of New York and State of New York, have invented certain new and useful Improvements in Gate-Valves, of which the following is a specification.

This invention relates to certain improvements in that class of gate-valves in which the faces of the gate are automatically forced to their seats by means of oppositely-inclined planes on their adjoining surfaces when the gate or valve is forced home by the valve-stem.

The object of this invention is to provide a gate-valve in which the valve is of two parts and the valve-seats opposite and parallel to each other with means for guiding the parts of the valve to their seats when the gate or valve is inserted in its chamber, thereby saving a great deal of time and trouble in readjusting the parts of the valve when they have been separated for cleaning or any other purpose.

In the drawings, Figure 1 represents a longitudinal sectional view of my improved gate-valve; Fig. 2, detached perspective views of the disks forming the gate. Fig. 3 is a cross-sectional perspective view on a plane through the middle of the gate-chamber; Fig. 4, detached perspective views of the packing-seat, packing, and confining-ring, and a diametric section of the recessed head of the valve-stem casing.

The letter A indicates the valve-chamber, which is of the usual construction; and B, the valve-seats, which are directly opposite and parallel to each other, and located, respectively, at the induction and eduction ports of the valve-chamber.

The letter C indicates the gate or valve, consisting of two circular disks, c c', of such diameter as to cover and close the induction and eduction ports of the valve-chamber when forced home against their seats. The disk c is provided with an inclined or beveled convex projection, d, on its inner face, and the disk c' on its inner face with an oppositely-inclined concave projection, d'. Each disk is provided at the top with a recess, e, in which a shoulder, D, on the valve-stem E is adapted to engage, in order to move the disks simul-

taneously in a straight line away from each other, so as to impinge closely and evenly upon the seats B.

The letter F indicates two inclined guides on opposite sides of the valve-chamber above the valve-seats B, the object of which is to guide the valve to its seat when it is first inserted in the valve-chamber, and prevent the two parts from spreading when the valve is raised to renew the packing of the valve-stem, 60 as more fully hereinafter explained.

The letter G indicates a shoulder formed on the valve-stem, and H an annular packing surrounding said valve-stem above the shoulder, and setting in a recess, I, of the casing, in 65 which it is confined by means of a ring, K, which is held in place by the screw-cap L.

Resting against the inner wall or shoulder of the annular recess I is an annular plate or ring, M, which serves as a seat for the said 70 packing.

The object of the shoulder on the valve-stem is to strike the plate or ring M and force it and the packing out of the recess I when it is to be renewed, and thus obviate the necessity of 75 picking it out by means of a sharp or pointed instrument, which is a tedious and inconvenient operation, and is liable to injure the surrounding metal.

The annular packing is beveled on top and 80 flat on the bottom, the beveled top portion resting on a correspondingly-shaped recess in the confining-ring K, by means of which it is securely forced against its seat; and said packing is preferably constructed of a compound 85 of rubber and plumbago.

The convex and concave projections on the adjoining faces of the respective disks bear against each other, and are adapted to work together to force the disks apart against their 90 respective seats when the gate or valve is forced home by the valve-stem.

The valve-stem is provided with a male screw-thread, which works in a female screw-thread in the cap of the valve-chamber, as 95 usual.

I am aware that a gate-valve has been constructed with a chamber having walls and valve-seats inclined toward each other from the entrance of said chamber, and that the in- 100

elation of said wall causes the parts of the valve to slide to their seats; but these seats are also inclined, and therefore necessitate a peculiar construction and action of the spindle in order to force them to their seats. I do not claim this construction.

What I claim is—

In combination with the valve C, constructed in two parts, with inclined bearing-faces, and the valve-rod, the valve-chamber A, having parallel valve-seats and provided at its

upper part with the inclined guides F, for guiding the valve to its seat during its insertion, substantially as specified.

In testimony that I claim the foregoing I have hereunto set my hand and seal in the presence of the subscribing witnesses.

HENRY MATHER. [L. S.]
